CLOTH MARKING DEVICE

Wilfrid Earle Fitzpatrick, Detroit, Mich., assignor
to The Murray Corporation of America, a cor-
poration of Delaware

Application June 16, 1930, Serial No. 461,621

10 Claims. (Cl. 33—36)

Although the present invention is referred to merely as a cloth marker, the apparatus disclosed is designed particularly to mark cloth which is to be made up into seat cushions and back cushions for use in automobiles, and the like.

It is an object of the invention to provide an organization in which adjustably spaced markers, such as special pens or wheels provided with separate means for delivering a marking liquid thereto in fine lines, may have a light but reliable rolling contact with sheets of cloth supported by means such as a substantially horizontal table. The latter may be held stationary during each marking; and the markers may be so arranged as to stripe or otherwise subdivide the cloth by narrow but distinct lines in preparation for sewing it in pleats,—within which padding may be subsequently stuffed. Preferred embodiments of the invention contemplate the attendance of two operatives facing one another and alternately removing sheets from an intermittently rising stack; said embodiments may accordingly include not only means to effect a relative horizontal reciprocatory or translatory motion between the mentioned table and a bar carrying a series of pens or rollers, said bar preferably advancing in a plane parallel with that of said table while the latter is held stationary, but also means for intermittently raising and rapidly lowering said table in a plane substantially at right angles to that of the mentioned translatory motion.

It is a general object of this invention to do away with reliance upon hand labor, using frames and a chalk which tends to produce lines of undue breadth, in the marking of sheets; and other objects of the present invention, including the provision of fixed standards which are spaced from the ends of said table and which preferably carry not only guides for the table and guides for the ends of the mentioned rods but also means for intermittently and synchronously elevating said ends, may be best appreciated from the following description of an illustrative embodiment of the invention, taken in connection with the appended claims and the accompanying drawings.

Fig. 1 is an elevational view, with parts shown in section.

Fig. 2 is a top plan view with some parts broken away to about the level of line 2—2 of Fig. 1 and other parts omitted.

Fig. 3 is an end elevational view, with parts broken away to various levels.

Referring first to the more general features of the invention, the illustrated embodiment thereof comprises a table T, vertically adjustable

relatively to standards S, S', disposed at the lateral ends thereof and comprised in a main frame F, a bar B, on which marking pens and/or wheels P are secured at spaced intervals; slideable brackets SB, SB' at the respective ends of the bar B, synchronously advanced by threaded rods R, R'. The latter may be rotatable within guide channels C, C' on the tops of the standards S, S'; and transmission means including shafts and gears are shown as employed to rotate the threaded rods R, R' from a motor M,—separate transmission means being used to manipulate the table T, or its equivalent.

As to preferred details, the standards S, S' are shown as secured to a base member 21, upon which the motor M is mounted; and said standards may serve to support not only the mentioned horizontal guide channels C, C' but to provide integral vertical flanges 22, 22' and 23, 23', oppositely extending and adapted to interfit with flanges 24, 24' and 25, 25', shown as provided upon depressed lateral extensions 26, 26' integral with the table T.

The table T may carry a stack of say 50—150 sheets for successive removal; and it may be raised and lowered by any suitable means. For example wells 27, 27' provided adjacent lateral edges of table T by the depression of the extensions 26, 26' may receive the brackets SB, SB' when said table is elevated; and the latter may be not only adjusted but supported by means including a pair of vertical screws 28, 28', shown as cooperating with threaded socket elements 29, 29' carried by the mentioned extensions. In case rotation is to be imparted to sockets 29, 29', rather than to the screw elements 28, 28' to raise and lower the table T, said sockets may be provided with either manual or power means for their simultaneous manipulation. For example, said screw elements being secured near their upper end by means such as bolts or pins 30, 30' extending through openings 31, 31' in eyes on said screws and through corresponding openings in webs 32, 32' integral with table T, the respective sockets 29, 29' may each be provided at one end thereof with a retaining collar 33 and at their other end with a beveled gear,—the illustrated gears 34, 34' being adapted to be synchronously driven from any suitable common source of power such as mentioned motor M by means hereinafter described. For example gears 34, 34' may be engaged by gears 35, 35' on an inner shaft 36 carrying special ratchets 37, 37' adapted to impart opposite rotation thereto from motor-driven shafts 38,—as by engagement of a splined-on clutch element 39 with either a table-

100
105
110

lifting clutch element 39' or a table-lowering clutch element 39''. The latter is shown as adapted to act rapidly through gears 40, 40' and chain 40'', whereas the latter is intended to act 5 slowly and intermittently through gears 41, 41', a reducer train between shafts 42, 42' in housing 43, a variable-radius crank 44 on shaft 42', a link 44' and a reciprocable arm 45 of the ratchet 37. To vary the movement of the table T per revolution 10 of the shaft 42', the arm 44 is shown as provided with a slot 46 in which a wrist pin 47 is adjustable upon the loosening of a nut 48; and balls 49 in tapering slots 50 in an inner member 51 will be understood to bind relatively an outer 15 member 52 during only the outward or lifting strokes of arm 45.

As to the reciprocation of marking elements P during intervals of rest in the elevation of table T, in case manual reciprocation is to be obviated 20 and in order to provide a sliding connection, of dove-tail type, between each bracket SB, SB' and corresponding guide elements such as channels C, C', the latter may include removable sections 53, 53'; and the respective brackets may be provided 25 with cylindrical members 54, engaged by springs 55 in corresponding openings in said brackets and including slidable and rotatable thread-engaging pins 56. The object of providing for at least a limited rotation of each pin 56, or 30 its equivalent, may be best appreciated from an inspection of Fig. 3,—diagrammatically showing the somewhat elliptical configuration preferably given to the thread-engaging portions of said pins and showing also the relationship to a "loop", 35 preferably provided in the threads upon the rods R, R' near the respective ends thereof, for a reversing effect. By this construction, continuous rotation of said rods may cause the brackets SB, SB', and all parts carried thereby, to reciprocate 40 back and forth across the table T, or its equivalent.

At the respective ends thereof, the guide channel elements C, C' may carry plates 57, 57' and 58, 58' and also support bearings as shown at 59, 45 60 and 61, Fig. 3; an extension or terminal portion 62 at one end of each of the shafts 16, 16' may have secured thereto rotating means such as a bevel gear 63; and any suitable means may be employed to transmit motion from the motor M or 50 its equivalent, to said bevel gears. For example, vertical or inclined shafts 64, may extend through suitable bearings provided by brackets 65, 66, respectively, carried by the standards S, S',—the respective ends of said shafts being provided with 55 beveled gears 67 and 68; and the latter may be rotated by means such as additional beveled gears 69, terminally provided upon shaft 38. The latter is shown as extending through bearing brackets 70, 70' and as including flexible couplings 71, 71' 60 on opposite sides of a gear housing 72. Said housing being optionally adapted to receive not only a worm gear but also to provide bearings for a worm and a shaft 72' of the motor M, said shaft containing couplings 73, 74, it will be seen that 65 manipulation of a suitable switch, not shown, may serve to control the travel of the transverse bar B, as carried by the mentioned brackets SB, SB'; and said bar may be provided with any desired marking devices, but preferably with such as permit a marking effect during movement in either horizontal direction across the top of table T.

As a matter of economy and practical expediency, even when the marker-carrying shaft or bar B is not intended to rotate, it may be 75 circular in cross-sectional outline; and it may

then be held against rotation relatively to the brackets SB, SB', in any suitable manner. For example, each of these brackets may be provided with an upstanding lug 75 having a part-cylindrical face 76 also a transverse opening for 80 some fastening element 77, serving movably to secure a cooperating clamp element 78 having a cooperating semi-cylindrical face 79; and the latter may be yieldably or otherwise held down, during marking operations, by means such as 85 pivoted bolts 80 carrying wing nuts 81.

In order to facilitate adjustment of the markers P, (shown as having the form of rollers or wheels with comparatively sharp edges 82 and 90 adapted to receive rotation by engagement with the goods) and in order to support thereabove means for the delivery of a marking fluid there- 95 to when desired and at a regulable rate, said markers may be carried by bearing organiza- 100 tions each comprising a sleeve 83 and each pro- vided with both an integral bearing collar 84 and a removable bearing collar 85; and the lat- 105 ter may be secured by means such as set screws 86, serving also to retain said sleeves upon the shaft or bar 12. One of the mentioned collars 110 (as the collar 84) may, in some or all instances, be adapted to include or to receive a post 87, extending upwardly therefrom and serving to support any suitable device for the delivery of 115 a marking liquid, or the like. For example, 120 each post may adjustably carry a support 88 for a wick or absorbent roller 89, disposed below a reservoir 90,—said reservoir being shown as provided with a valved outlet 91, adjustable by 125 means such as a handle 92, extending through a 130 cover 93; but it will be obvious that such details as have just been referred to are comparatively immaterial to the broader aspects of present invention,—especially in view of the fact that some or all of the "markers" P may, if desired 135 have the form of pens or other means for reli- 140 ably producing narrow and distinct lines even upon fabrics.

The table T may be reinforced by means such as vertical or other webs 94 therebelow; but so 145 positioned as to avoid encounter with mentioned parts or with bearing brackets 95 for shaft 36. Stacks containing (say) 50 to 100 sheets 96 of a pile fabric, or the like, may be brought to the table on templets 97, corresponding in outline 150 to the sheets of a stack and placed upon the table T while the markers P occupy some position beyond a rear edge or front edge of said table. It will be understood that said table, after being brought to a level suitable to the intended effect, may remain stationary during each actual marking of a sheet; that the adjustment of crank pin 47 is intended to be such as to compensate the removal of a sheet and that the actual marking may be effected by means of a marking liquid applied through markers of any preferred type. Two operatives are ordinarily stationed 155 face to face and one sheet of fabric is removed during a pause after each "pass" of the bar B and during a quick compensatory elevation of table T; and a shifting of the clutch element 39, by a lever 98 from a position of engagement 160 with clutch element 39' to a position of engagement with the clutch element 39'', will be seen to have the effect of rapidly lowering table T in 165 readiness to receive a new stack of sheets.

Although the foregoing description has included complete details of but one embodiment of the present invention, it should be understood not only that various features thereof might be 170 independently employed but also that numerous 175

modifications, additional to any suggested herein, might easily be devised by skilled workers if informed of the foregoing,—all without departure from the scope of the present invention, 5 as the latter is indicated above and in the following claims.

I claim:

1. In a marker: a table for the support of super-
posed sheets to be successively marked, marking
elements mounted for reciprocation in a plane
parallel therewith and in engagement with said
sheets, and driving means for automatically rais-
ing said table each time a sheet is marked. 10
2. In a marker: a table for the support of super-
posed sheets to be successively marked, a
plurality of rotatable marking elements recipro-
cable means for supporting said marking ele-
ments in spaced relationship to one another and
to said table and rotatable by engagement with
said sheets during reciprocation of the support
for said marking element in a plane parallel with
said sheets, and driving means for automatically
raising said table at the end of each movement
of the elements. 20
3. In a marker: a table for the support of super-
posed sheets to be successively marked, a plu-
rality of marking elements, reciprocable means
for supporting said marking elements in spaced
relationship to one another and to said table and
in engagement with said goods during a relative
reciprocation between said table and the marking
elements in a plane parallel to said table, and
means for effecting such reciprocation, said table
being vertically adjustable to bring successive
sheets into engagement with the marking ele-
ments and provided with means for guiding its
vertical movement. 30
4. In a marker: a table for the support of super-
posed sheets to be successively marked, a
plurality of marking elements supported in spaced
relationship to one another and to said table and
movable in a plane parallel therewith, said table
being provided with means for effecting its in-
termittent elevation toward the marking elements
to bring successive sheets into engagement there-
with. 40
5. In a marker: a table for the support of super-
posed sheets to be successively marked, a plurality
of marking elements supported in spaced rela-
tionship to one another and to said table, means
for producing reciprocation between said table
and said elements in a plane parallel with said
table, means for raising said table, and driving
means for effecting the reciprocatory movement
of the elements and the raising of the table in
timed relationship. 50

means for effecting the reciprocatory movement
of the elements and the raising of the table in
timed relationship.

6. In a marker: a raisable table for the sup-
port of superposed sheets to be successively marked,
and a plurality of marking elements sup-
ported in spaced relationship to one another and
to said table, a transverse bar upon which said
marking elements are mounted, and means ef-
fecting relative reciprocation between said table
and said bar in parallel relationship during the
time the table is being raised. 80

7. In a marker: a table for the support of
superposed sheets to be successively marked, a
plurality of marking elements supported in
spaced relationship to one another and to said
table, a transverse bar upon which said marking
elements are mounted, and screw means provided
at opposite ends of said bar for intermittently ele-
vating said table in a direction substantially per-
pendicular to the top thereof to bring successive
sheets into engagement with the marking ele-
ments. 90

8. In a marker: a table for the support of super-
posed sheets to be successively marked, a plu-
rality of marking elements supported in spaced
relationship to one another and to said table, a
transverse bar upon which said marking elements
are mounted, and means for effecting a relative
movement between said bar and said table both
in a plane parallel to said table and in a plane
perpendicular to said table to bring successive
sheets into engagement with the marking ele-
ments. 100

9. In a power driven marker: a table for the
support of a stack of superposed sheets, marking
means mounted above said table for reciprocation
in a plane parallel thereto, means for intermit-
tently elevating said table relatively to the opera-
tion of said marking means, means for lowering
said table, upon the removal of said stack, to re-
ceive a new stack of sheets, and a power device
for operating said marker. 115

10. In a power driven marker: a table for the
support of a stack of superposed sheets, marking
means mounted for reciprocation in a plane
parallel to the table, means for intermittently ele-
vating said table relatively to the operation of
said marking means, means for reciprocating the
marking means, and a power device for operating
said marker. 120
